R. H. Richardson Atty:

UNITED STATES PATENT OFFICE.

RALPH W. ENGSBERG, OF LAKE MILLS, WISCONSIN, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed August 10, 1925. Serial No. 49,219.

The present invention relates in general to automatic telephone systems, and more specifically to an improved type of secondary rotary line switch to be used with plunger (Keith) type primary line switches for extending calling lines to first selectors. In a system of this character the idle primary line switches of a group are held poised over the bank springs of an idle trunk by a master switch, and when a call is initiated the primary line switch plunges to seize the idle trunk. The secondary line switch terminating the seized trunk immediately connects with a selector if its wipers happen to be standing upon the bank contacts of a trunk terminating in an idle selector; or if its wipers are standing upon the bank contacts of a busy trunk, they are automatically rotated step by step until they find an idle trunk whereupon the rotation is stopped.

The foregoing describes the operation of the known arrangement. This invention, however, provides an improved type of rotary secondary line switch which materially speeds up the service by a preselecting action. The improved line switch does not preselect at once when released but is caused to preselect by the primary master switch, when the master switch comes to rest on the particular trunk which extends to the secondary line switch in question.

The invention will be more clearly understood by reference to the accompanying drawing, which shows a circuit diagram of the equipment.

Referring to the drawing, the apparatus shown in the circuit diagram may now be briefly described. The substation A is an ordinary automatic telephone substation having the usual talking instrumentalities and a calling device for controlling the automatic switches. The line conductors terminate at the exchange in the individual line switch C, which is of the well known plunger type, to be hereinafter explained in detail in connection with its operation.

The master switch D is of the type shown and described in Automatic Telephony by Smith and Campbell, second edition, pages 48, 49 and 50, modified however, to include an additional set of bank contacts and wiper.

The secondary line switch F is a non-numerical switch mechanically of the well

known rotary type in which the wipers have no normal position and move in a forward direction only. Relay 61 is a socalled two step relay. The springs represented by armature 64 and working contact are closed on the first step, while the springs represented by armature 65 and its contact are not closed until the second step, that is, until the relay is fully energized.

The first selector E, shown only in part, is mechanically of the usual and well known Strowger vertical and rotary type.

Having briefly explained the purpose of the invention and the apparatus involved in carrying it out, the operation of the equipment may now be explained more in detail. For this purpose it will be assumed that the subscriber of substation A desires to obtain a connection.

When the calling subscriber at substation A removes his receiver to initiate the call, an energizing circuit is completed for the line relay 14 of the line switch which may be traced from ground, right-hand winding of supervisory relay 31 of the master switch D, conductor 30, resting contact and spring 20, line conductor 11, over the subscriber's loop and return to line conductor 12, resting contact and spring 21, and line relay 14 to battery. Upon energizing, line relay 14 closes an energizing circuit at armature 19 for the pull-in winding 18, which may be traced from ground at relay 31 and said relay, conductor 30, working contact and armature 19, pull-in winding 18, conductor 36, and armature 32 and its resting contact to battery. Pull-in winding 18, upon energizing, operates both the plunger arm 15 and the cut-off armature 16; the former, through the medium of its plunger (not shown), forces the bank springs 24-26, inclusive, into engagement, respectively, with the contacts 27-29, inclusive, and the latter disconnects the line conductors 12 and 11 from the line relay 14 and from ground, respectively. By the engagement of bank springs 24-26, inclusive, with contacts 27-29, inclusive, the line and holding conductors are extended to the secondary line switch F.

By the extension of the line conductors at bank springs 24 and 26 and contacts 27 and 29, a circuit is closed for the line relay 61 of secondary line switch F as follows:

ground, resting contact and armature 73, bank contact 29, bank spring 26, line conductor 11, over the subscriber's loop and return to line conductor 12, bank spring 24, 5 bank contact 27, armature 66 and its resting contact, and relay 61 to battery. Relay 61 is a socalled two step relay and is already partially energized under control of the master switch to hold armature 64 attracted. 10 This relay now fully energizes and attracts armature 65, which closes a circuit by way of bank contact 28 and spring 25 for the hold winding 17 of the primary line switch C, and places ground potential by way of 15 conductor 13 on the multiple test contacts in the banks of connector switches having access to the line of substation A, whereby said line is made busy. Line relay 14 is made slow-acting and holds the circuit of 20 pull-in winding 18 closed until ground potential is returned by the secondary line switch F for hold-winding 17, which winding is insufficient to operate the plunger arm, but is sufficient to hold said arm after it has 25 operated.

As a further result of the attraction of armature 65 of the secondary line switch F, a circuit is closed through the master switch D, whereby said switch is operated in the 30 well known manner to advance the fully restored plungers of the remaining idle line switches into position before the terminals of the next idle trunk line. During the operation of the master switch the circuit including the pull-in windings such as 18 is 35 opened at armature 32 to prevent the plunging of a line switch during rotation.

As a still further result of the attraction of armature 65, it closes a circuit for relay 40 62 in series with rotary magnet 63, the latter not energizing in this circuit due to the high resistance of the former. Relay 62, upon energizing, disconnects the relay 61 from the master switch D at armature 68; 45 disconnects the rotary magnet 63 from the selector E at armature 67; and at armatures 66 and 73, disconnects the trunk conductors from the relay 61 and ground and extends them to the wipers 70 and 72, respectively, 50 thus closing a circuit for the line relay 80 of the selector E which may be traced as follows: ground, lower winding of line relay 80, resting contact and armature 84, bank contact 76, wiper 72, working contact and armature contact and armature 73, bank 55 contact 29, bank spring 26, line conductor 11, over the subscriber's loop and return to line conductor 12, bank spring 24, bank contact 27, armature 66 and its working contact, wiper 70, bank contact 74, armature 83 and its resting contact, and upper winding of 60 relay 80 to battery. Relay 80, upon energizing, closes a circuit for release relay 81, which energizes to connect ground to the release 65 trunk conductor at armature 82 to hold the

preceding switches in operated condition. The relay 61 being slow to release, holds up until this ground potential is returned by the selector E.

The calling subscriber may now operate 70 his calling device in accordance with the first digit of the called number, and the selector E will raise its wipers to the correct level and rotate in to select an idle trunk leading to a succeeding switch, whereupon 75 its switching relay will operate to extend the connection. Ground potential is returned from the last seized switch, up to and including the connector, over the holding conductor to hold the preceding 80 switches; all of which is in the usual well known manner. The connector tests the called line and if found busy it denies the connection and gives a busy tone to the calling subscriber who restores his receiver. If, 85 however, the called line is found idle the connector completes the connection and rings the called party's bell. The called party, upon answering, by lifting his receiver, stops the ringing and completes the talking 90 circuit, whereupon the subscribers may converse as desired.

The calling subscriber will finally terminate the conversation, and will replace his receiver, bringing about the disconnection 95 of the apparatus in the usual manner. Briefly, upon the deenergization of the line relay at the connector (not shown), its release relay deenergizes and breaks the holding circuit of the preceding switches, whereby all the switches including the selector E, secondary line switch F, and primary line switch C are restored to normal position. When relay 62 of the line switch F falls back and armature 68 engages its resting contact, 105 relay 61 is not energized because wiper 34 of the primary master switch has passed off from contact 33.

Eventually the master switch will again come to rest with its wipers as shown and 110 a circuit is closed for the two-step relay 61 which may be traced from grounded sliding contact 35, wiper 34, contact 33, resistance 69, resting contact and armature 68, and relay 61 to battery. Relay 61 only energizes 115 partially in series with resistance 69 to operate armature 64 and prepare a circuit for the stepping magnet 63. If the trunk upon which the secondary line switch is resting is 120 busy, ground potential will be present on the release trunk conductor and a circuit may be traced from ground, armature 82 and its working contact of selector E, contact 75, wiper 71, armature 67 and its resting 125 contact, working contact and armature 64, and stepping magnet 63 to battery. Stepping magnet 63 will energize over this circuit and operate to step the secondary line switch to the next succeeding trunk, etc., 130 until an idle trunk is found, whereupon the

stepping is stopped due to the absence of ground potential on the release trunk conductor.

From the above it will be seen that an 5 idle trunk is preselected by the secondary line switch under control of the master switch.

Having described my invention, what I 10 consider to be new and desire to have protected by Letters Patent will be pointed out in the appended claims.

What is claimed is:

1. In a telephone system, a non-numerical switch having wipers which normally stand 15 on the trunk line last used, a plunger line switch controlled over a calling subscriber's line for seizing said non-numerical switch, a master switch for positioning said line switch before said non-numerical switch, 20 and means responsive to the operation of said master switch for causing said non-numerical switch to seek an idle trunk line.

2. In an automatic telephone system, a non-numerical switch, trunk lines accessible 25 thereto terminating in contacts, means for making certain of said trunks busy, wipers for said switch normally standing on the contacts of one of said trunk lines, a relay in said switch operable in two stages, a 30 motor magnet for said switch, means for holding said relay operated in the first stage as long as said switch is in seizable position and yet unseized, and means controlled by the operation of said relay in said first stage 35 for causing the operation of said motor magnet to move said wipers into engagement with the contacts of an idle trunk line.

3. In an automatic telephone system, a non-numerical switch, trunk lines accessible 40 thereto terminating in contacts, means for making certain of said trunks busy, wipers for said switch normally standing on the contacts of one of said trunk lines, a relay in said switch operable in two stages, a 45 motor magnet for said switch, means for holding said relay operated in the first stage as long as said switch is in seizable position and yet unseized, means controlled by the operation of said relay in said first stage 50 for causing the operation of said motor magnet to move said wipers into engagement with the contacts of an idle trunk line, and means controlled over a calling subscriber's loop for operating said relay in its 55 second stage to extend a connection to said idle trunk line.

4. The combination, with a plurality of primary plunger line switches each individual to a subscriber's line, of a plurality 60 of secondary rotary line switches accessible to said primary switches, a group of trunk lines accessible to said secondary switches, a master switch operated responsive to the seizure of one of said secondary switches for 65 positioning the idle primary switches before

an idle secondary switch and means effective when idle primary switches are placed opposite an idle secondary switch for causing said idle secondary switch to hunt for an idle trunk.

5. In a telephone system, a primary line switch, a plurality of secondary line switches, a plurality of trunks accessible by way of said primary switch and one of said secondary switches connected in series, a master 70 switch arranged to preselect the secondary switch next to be used, means operated responsive to the selection of the secondary switch for selecting an idle trunk, a relay in the secondary switch operated responsive to the operation of the primary line switch, means controlled by said relay for seizing the selected trunk, means for operating the master switch to select a different secondary switch for subsequent use responsive to the 75 operation of said relay, and means responsive to the seizure of the trunk to release said relay.

6. In a telephone system, the combination 80 with a plurality of primary line switches, of a plurality of secondary line switches accessible to each of the primary line switches, a plurality of trunks accessible to each secondary line switch, a master switch for pre-selecting an idle secondary switch, a relay 85 in each secondary switch operated responsive to the selection of the switch to cause the switch to hunt for an idle trunk, means for seizing the idle trunk, and connections controlled by said last named means for 90 releasing the first named relay.

7. In a telephone system, a primary line switch, a plurality of secondary line switches, a master switch for associating the primary line switch with an idle secondary line 105 switch, a plurality of trunks accessible to the secondary line switch, means operated responsive to the selection of the secondary line switch for operating it to hunt for an idle trunk, means for taking the secondary 110 line switch into use, said first named means being controlled by the master switch before the secondary switch is taken into use and over the talking conductors if when the secondary line switch is taken into use a 115 trunk has not yet been found.

8. In a telephone system, a primary line switch, a plurality of secondary line switches, a master switch for associating the primary line switch with an idle secondary line switch, a plurality of trunks accessible to the secondary line switch, means in the secondary line switch operated over either of two paths one of which is effective when the switch is preselected by the master switch and the other when the switch is taken into use, and means controlled by said first named means for operating the secondary line switch to select an idle trunk.

9. In an automatic telephone system, a 130

plurality of subscribers' lines, a plurality of primary line switches one for each line, a plurality of secondary line switches accessible to each primary line switch, each secondary line switch having a plurality of trunks accessible thereto, a master switch arranged to preselect an idle secondary switch, means in each secondary switch operated only when the switch is preselected to select an idle trunk, and means operated responsive to the operation of the primary line switch to indicate a busy condition of the calling line.

10. In an automatic telephone system, a subscriber's line, a primary line switch, a plurality of secondary line switches, a plurality of trunks accessible to the line by way of said primary switch and a secondary switch connected in series, an automatic switch terminating each trunk, a master switch arranged to preselect the secondary switch next to be used, means operated responsive to the selection of the secondary switch to select an idle trunk, means operated responsive to the initiation of a call to seize the preselected secondary line switch and the preselected idle trunk, means at the automatic switch operated when the switch is seized to indicate a busy condition of the automatic switch and of the secondary line switch.

11. In an automatic telephone system, a subscriber's line, means for extending calling connections to the line, means including a primary line switch, a plurality of secondary line switches accessible thereto, and a plurality of directly operated automatic

switches accessible to the secondary line switch for extending calling connections from the line, a master switch for preselecting an idle secondary line switch for subsequent use, means in the secondary line switch operated responsive to its selection to select an idle automatic switch, and means in the secondary line switch operated responsive to the initiation of a call over the line to prevent the establishment of calling connections to the line.

12. In an automatic telephone system, a subscriber's line, means for extending calling connections to the line, means including a primary line switch, a plurality of secondary line switches accessible thereto, and a plurality of directly operated automatic switches accessible to the secondary line switch for extending calling connections from the line, a master switch for preselecting an idle secondary line switch for subsequent use, means in the secondary line switch operated responsive to its selection to select an idle automatic switch, means in the secondary line switch operated responsive to the initiation of a call over the line to prevent the establishment of calling connections to the line to seize the automatic switch, and to operate the master switch to select a different secondary line switch for subsequent use, and means at the subscriber's line for directly operating the seized automatic switch.

In witness whereof, I hereunto subscribe my name this 3rd day of August, A. D., 1925.

RALPH W. ENGSBERG.
